UNITED STATES PATENT OFFICE

ANDREW J. CARMICHAEL AND ALBERT M. WUNDERLICH, OF NEW HAVEN, CONNECTICUT, ASSIGNOR TO THE GREIST MANUFACTURING COMPANY, A CORPORATION OF CONNECTICUT

SEWING-MACHINE-ATTACHMENT HOLDER

Application filed December 29, 1927. Serial No. 243,350.

This invention relates to a holder for sewing machine attachments by which various attachments may be conveniently secured to the presser-foot of a sewing machine. 5 The improved attachment holder preferably consists of a clamp comprising two jaws adapted to engage the horizontal or vertical portion of a sheet metal presser foot, said jaws being preferably forced together for a 10 clamping operation by means of a thumb screw passing loosely through the upper jaw and tapped in the lower jaw. Integral with this clamp is an extension to which an attachment or attachment support may be secured 15 in any proper manner, as by rivets.

In the accompanying drawings Fig. 1 is a side view of one form of the improved attachment holder, showing the same in operative relation to the presser foot of a sewing machine, with the braider or corder mounted thereon. Fig. 2 is a rear view of the attachment holder looking from the right of Fig. 1, with the part of the presser foot engaged by the clamp in section. Fig. 3 is a 20 plan view of the attachment holder shown in Figs. 1 and 2 with the braider or corder omitted. Fig. 4 is a plan view of an approved form of the improved attachment holder with a binder mounted thereon. Fig. 25 5 is a plan view of the attachment holder with an edge-stitcher guide attached thereto. Fig. 6 is a plan view of the attachment holder shown in Figs. 4 and 5, without any attachment. Fig. 7 is a section on line 7-7, 30 Fig. 4. Fig. 8 is a view similar to Fig. 2, showing a cam lever for forcing the jaws of the clamp together. Figs. 9 and 10 show a form of clamp extension adapting the clamp to be attached to the vertical part of the 35 presser-foot, and Figs. 11 and 12 illustrate a form of clamp similar to that shown in Figs. 9 and 10 but adapted to engage a sewing machine presser-bar.

Referring to the drawings, 12 denotes the 40 foot portion of a sheet metal presser foot of well known form, and 13 denotes the upper horizontal part of the shank of said presser foot. The improved attachment holder comprises a clamp 16 having upper and lower 45 jaws, and, integral with the lower jaw of

said clamp, in the form of the invention shown in Figs. 1 to 8, inclusive, is a depending part 17 having at its lower end an integral horizontal extension 18, these parts 17 and 18 constituting an integral extension 55 to which a sewing machine attachment may be secured. Passing loosely through the upper jaw of said clamp, and tapped in the lower jaw thereof, is a thumb screw having a knurled head 19. A washer 20 will preferably be interposed between the shoulder of the thumb screw and the upper jaw of the clamp 16. 60

To prevent displacement of the holder relative to a presser-foot shank to which said holder is to be secured, and to facilitate the positioning of the holder on the presser-foot shank, the jaws of the clamp 16 are preferably provided with shoulders 27 which engage the sides of the presser-foot shank 13, 70 as clearly shown in the drawings.

In Fig. 1 a braider or corder 21 is shown as being mounted upon an inclined support 22 the lower horizontal part of which is shown as being riveted to the horizontal extension 18. This braider or corder forms no part of the present invention, the same being fully shown and described in our application Serial No. 225,916, filed October 13, 1927. 75

Fig. 4 shows the improved attachment holder adapted for supporting a binder attachment 23, this form of the holder being the same as that represented in Figs. 1, 2 and 3 excepting that the horizontal extension 18 at the lower end of the depending portion of the clamp member is provided with a lateral extension 18^a on which the binder support 24 is mounted. 85

Fig. 5 shows an edge stitcher guide 25 90 mounted on a holder of the same form as that illustrated in Fig. 4, the holder illustrated in Figs. 4 and 5 being shown in plan in Fig. 6, with the attachments omitted.

The lateral extensions 18^a are provided 95 with small struck-up lugs 18^b on opposite sides of the hole 18^c for the rivet 26, and the shanks 24^a and 25^a of the parts 24 and 25, are each provided with a slot 26 receiving said lugs, this construction permitting 100

slight lateral adjustments of the parts 24 and 25, said parts being frictionally held in place by plate springs 28 beneath the heads of the rivets 26.

Fig. 8 is a view similar to Fig. 2, but showing a cam lever 19^a, instead of a set screw, for closing the jaws of the clamp 16 together.

Figs. 9 and 10 show a construction of clamp adapted to engage the vertical portion 19 of the presser foot 12 by virtue of the fact that the extension 17^a is in line with the clamp instead of being at right angles thereto as in the construction most clearly shown in Figs. 1 and 2.

Figs. 11 and 12 show a form of clamp similar to that illustrated in Figs. 9 and 10 but with the jaws of the clamp made in suitable form for embracing a sewing machine presser bar 29.

From the foregoing it will be understood that the invention provides an efficient sewing machine attachment holder adapted to be secured to a presser member of a sewing machine and consisting, except for the set screw or cam lever, of a single piece of sheet metal (preferably steel) so that it may be made at little expense.

Having thus described our invention we claim and desire to secure by Letters Patent:—

1. A one-piece sewing machine attachment holder comprising a clamp adapted to embrace a sewing machine presser member and consisting of two integral sheet metal jaws, said clamp having, integral therewith, an extension to which a sewing machine attachment may be secured, combined with means for forcing the jaws of said clamp towards each other in rigidly affixing said clamp to the presser member.

2. A one-piece sewing machine attachment holder comprising a clamp adapted to embrace a sewing machine presser member and consisting of two integral sheet metal jaws, said clamp having, integral therewith, an extension to which a sewing machine attachment may be secured, combined with means for forcing the jaws of said clamp towards each other in rigidly affixing said clamp to the presser member, said jaws having shoulders to prevent displacement of said holder.

3. A one-piece sewing machine attachment holder consisting of a clamp having an integral depending part provided at its lower end with a horizontal extension by which a sewing machine attachment may be supported, said clamp comprising two jaws adapted to receive between them a part of a sheet metal presser foot, and means by which said jaws may be closed together.

4. A one-piece sewing machine attachment holder consisting of a clamp having an integral depending part provided at its lower end with a horizontal extension by which a

sewing machine attachment may be supported, said clamp comprising two jaws adapted to receive between them a part of a sheet metal presser foot, and means by which said jaws may be closed together, said jaws having shoulders to prevent displacement of the holder.

5. A one-piece sewing machine attachment holder comprising a clamp adapted to embrace a sewing machine presser member and consisting of two integral sheet metal jaws, said clamp, having, integral therewith, an extension to which a sewing machine attachment may be secured, combined with a thumb screw tapped in a jaw member of the clamp, for forcing said jaws towards each other in rigidly affixing said holder to said presser member.

In testimony whereof we affix our signatures.

ANDREW J. CARMICHAEL
ALBERT M. WUNDERLICH.
